United States Patent Office

GEORGE PENNOYER, OF NEW YORK, N. Y.

Letters Patent No. 75,698, dated March 17, 1868.

IMPROVEMENT IN THILL-COUPLING.

The Schedule referred to in these Letters Patent and making part of the same.

TO WHOM IT MAY CONCERN:

Be it known that I, GEORGE PENNOYER, of the city, county, and State of New York, have invented a new and useful Improvement in Noiseless Devices for Coupling Thills or Shafts on to carriages, and a novel manner of constructing the same.

My improvement consists of a double solid cone, permanently attached to and forming a part of the axle-clip; two solid conic caps to form a joint with the cones; a screw-bolt for a special purpose; and a close or secret joint; and I do hereby declare that the following is a full, clear, and exact description of my improvement, reference being had to the annexed drawings, which make a part of these specifications.

Figure 1 is a perspective view of an axle-clip with the double cone attached.

Figure 2, a drawing of the thill-strap and the solid conic-caps A A, screw-bolt, and close joint C.

Figure 3, the several parts combined as when in use.

To enable others more fully to understand, manufacture, and use my invention, I will now describe it in detail.

To construct my improved coupling, I provide a sufficient quantity of suitable iron or steel, from which I form the clip and double cone in one solid piece, (see fig. 1.) I then form the cone-caps upon separate pieces, which are to be rights and lefts, and one of these pieces is to be much broader, longer, and therefore stronger than the other. This piece forms the greater and stronger section or portion of the thill-strap, or that portion that is necessary to be bolted to the shaft, and is to be placed upon the outer side or next to the wheel, in order to receive the greater strain when turning the carriage. This portion of the strap is narrowed for a few inches back from the cap, at the terminus of which narrowing is formed the socket or female portion of the secret joint C. This socket is formed by boring down to a proper depth from the inner or upper side of the strap. The smaller or inner section of the strap is formed with the male portion of the hinge upon the unfinished end, and is fitted in such a manner as to form a capped or closed joint, the working of which is not seen from either side of the strap when the same is bolted to the shaft or thill, as shown at fig. 3; the two parts of this joint being fitted and riveted together, and the two sections of the strap properly fitted to each other, with the screw-bolt B, which passes through the smaller or inner section of the strap, and is threaded into the outer or stronger portion of the strap, thereby avoiding the use of a nut, the object of this bolt being to strongly hold and fasten the cap upon the cones when in use. These caps are bored and fitted to the cones in such a manner as to be used with or without packing, as may be desired. Thus ends the construction, all of which will be more readily understood by referring to the drawings.

The advantage and operation of my invention are, that the clip and double solid cone being made of one piece of metal insures extra strength and utility; the taper of the cones with the corresponding cap creates a constant bearing, which prevents the usual rattling noise; the bolt holds the cap strongly upon the cones, and facilitates the coupling and uncoupling of the shafts to the carriage; the cone-caps being solid, they exclude dust and dirt, and form boxes for oil or packing; the capped or closed joint is strong, easy of construction, and gives elegance of finish.

What I claim as my invention, and desire to secure by Letters Patent, is—

1. The double solid cone, in combination with the clip, fig. 1.
2. The solid conic caps A A, in combination with the solid cones.
3. The screw-bolt, in the position and for the purposes described.
4. The capped joint in constructing a carriage-coupling, as and for the purposes described.
